CUTTING IMPLEMENT

Nicholas V. Casson, New York, N. Y.

Application January 20, 1938, Serial No. 185,851

10 Claims. (Cl. 30—144)

This invention relates to cutting implements. The special object of the invention is to provide a cutting implement of the portable hand-tool type, for use on BX cable and the like, and a novel and valuable such implement because incorporating not only a hack-saw, for cutting the armor of the cable without injuring the insulation sheath therein, but also a shear means in the nature of a pair of snips, for cutting the 10 conducting wire within the sheath, or the sheath, or both.

The combination in one portable hand tool of a hack-saw and a shear means has not to my knowledge heretofore been suggested.

By the present invention, moreover, such a combination is fabricable at trifling cost and is otherwise entirely practical, because of the few parts required, because thin sheet metal can be used for all the principal parts of the tool, because there need be merely two or three pieces of thin sheet metal present for providing the blade holder and the handle for the hack-saw and also for providing the shear means, and because riveting or the like is reduced to a minimum, yet the blade holder is of strong and rigid character and the handle can be comfortably held when the implement is used as a hack-saw for the reason that then the handle is of a thickness which is a multiple of the thickness of the 30 sheet metal employed.

The invention consists in certain novel features of construction and combinations and arrangements of parts, the nature of which will appear clearly from the following description of 35 an illustrative embodiment of the invention as shown in the accompanying drawing, and the essential attributes of which will be pointed out in the claims following the description.

In the drawing—

Fig. 1 shows in side elevation an embodiment 40 of the invention as now preferred in which the hack-saw frame, its handle and the shear means are all made from merely two pieces of thin sheet metal.

Fig. 2 is a horizontal section, taken on the line 45 2—2 of Fig. 1.

Fig. 3 is a similar section, taken on the line 3—3 of Fig. 1, with the handle shown in closed position.

Fig. 4 is a view similar to Fig. 1, but showing 50 a modification in which the hack-saw frame, its handle and the shear means are all made from merely three pieces of thin sheet metal.

Fig. 5 is a horizontal section, taken on the 55 line 5—5 of Fig. 4.

Referring now in detail to the structure shown in exemplification of the invention in Figs. 1, 2 and 3, it will be noted that the entirety of the new tool, with the exception of a replaceable hack-saw blade 10, comprises in the main two 5 pieces 11 and 12 of thin sheet metal, conveniently stamped and formed to shape in a power press.

One of the these pieces of sheet metal, that marked 11, is cut and bent to provide a hack-saw frame having a plate-like portion 13 at one end extended laterally to form part of the thickness of a handle. The part 14 of the piece 11, from which the portion 13 is extended, constitutes a holder for the hack-saw blade 10 and at the same time a stop means to limit the effective cutting depth of the blade when the armor of a BX cable is sawed through by use of the blade 10 of the tool. Such stop means is afforded by the lower straight edges 15 extending lengthwise of the two sides of a U-channel within which the blade is seated when placed in and locked to the holder. This U-channel blade holder is provided by bending the part 14 of the piece 11 along a central longitudinal line of fold 25 as illustrated.

As shown, one side wall of the holder 14 is uniplanar with the plate-like portion 13 of the piece 11 which forms part of the thickness of the handle, while the other side wall of the holder is 30 cut off short and preferably along a line which over the major part of its length is arcuately curved as shown at 16. Also as shown, this wall last-mentioned, between its end 16, and a point near the adjacent end of the blade 10, is flattened in to lie close against the facing surface of the complementary wide wall of the holder, by being bent along a line 17 transverse to the holder.

In order readily to insert a blade 10 in the 40 holder, or to remove the blade 10 therefrom, as to substitute one blade for another, any suitable provision may be made. As shown, one side wall of the holder is cut away as indicated at 18, and then, when the U-channel in the holder of 45 a length to accommodate a blade 10, such a blade, of the common type and having mounting apertures near opposite ends, can be readily inserted or removed. For the taking of one of these apertures, a short cylindrical stud 19 is secured 50 as by riveting to the outer end of the holder, and for the taking of the other of these apertures a removable pin 20 is provided. This pin, having a cylindrical portion projecting from its mount oppositely from the stud 19, is on a mount which 55

here is in the form of a leaf-spring 21; and the end of this spring remote from the pin 20 is secured to the piece 11 by a single rivet 22. The holder 14 is apertured as seen best in Fig. 2 to receive the pin 20 incidental to seating of the latter in an end aperture in the blade 10 for mounting the blade in the holder. To remove the blade 10, as to replace the same with another, it is merely necessary to lift the pin 20 clear of the blade, by pulling outwardly on the free end of the spring 21, then swing the blade through 90° in its own plane until it extends as shown in dot and dash lines in Fig. 1, and then lift it clear of the stud 19.

15 The arcuate curvature 16 of the piece 11 matches and so bears against a similar terminal shaping of the piece 12 at its upper end. These curvatures are concentric with a rivet 23, which rivet, the sole rivet used in building up a handle 20 for the hack-saw frame which is of a thickness a multiple of the thickness of the piece 11, constitutes also a pivotal mounting for the piece 12. This piece 12, which has front and rear edges matchable with the front and rear edges 25 of the handle-forming portion 13 of the piece 11 when the piece 12 is swung from the position shown in dot and dash lines to a position of maximum overlap relative to said portion 13, can when desired be swung as last-described to cooperate 30 with said portion 13 in providing, as shown in Fig. 3, a hack-saw handle of adequate thickness for comfortable use despite the employment of relatively thin metal stock for the pieces 11 and 12. At the same time, the piece 12 can be 35 swung also as last-described, but for a special purpose, that is, to coat scissor-fashion with the portion 13 of the piece 11, in providing the usual two handles for a shear means in the nature of a pair of snips.

40 The cooperating snip elements or cutting edges of this shear means are shown at 24 and 25, the former on the piece 12 and the latter on the piece 11. The edge 25, it will be noted, is shown as part of a V-notch formed in a lateral extension 45 from the upper end of the handle portion 13 of the piece 11. As also here shown, each of these cutting edges has a general line of extension directed toward the axis of pivotal connection between the pieces 11 and 12 by way of the rivet 23.

50 Whenever, after cutting through the armor of a BX cable by application thereto of the blade 10, the contained insulation sheath, or the conducting wire in the latter, is to be cut by the shear means, the latter is set to cutting condition merely by swinging the piece 12 to the position shown. Then, with the two spread handle elements gripped in one hand, the part of the BX cable projecting beyond the cut end of the 55 armor is at the desired point along its length positioned between the cutting edges 24 and 25, and said handle elements are moved slightly to cause the cutting edges to take a biting grip on the insulation sheath, or on the conductor, as the case may be. For a straight cut through both 60 sheath and conductor, or through only the conductor if here bared, this is accomplished merely by forcing the handle elements toward each other and then to the full extent of mutual overlap which they occupy when constituting the handle for the hack-saw. If a cut through the 65 sheath only is to be made, this is readily done by gradually increasing the pressure on the handle elements while rotating the cable, or intermittently with rotations of the latter.

In forming the pieces 12 and 13, it is now preferred to shape the portion 13 of the piece 11, and the piece 12, as indicated respectively at 27 and 27a, to stiffen these handle forming parts in their planes of extension and to increase the thickness of the hack-saw handle when the same is established as such, along a grip length thereof.

Referring to the modification shown in Figs. 4 and 5, this is identical with the tool of Fig. 1, except that the entire structure comprising 10 hack-saw frame, its handle and the shear means are all made of three pieces of thin sheet metal instead of merely two, and except that the 15 detent for the end of the blade 10 which includes the leaf-spring 21, and the detent for the other end of the blade consisting of the stud 19, are on the same side of the tool as the piece corresponding to the piece 12 of Fig. 1.

By using three pieces of sheet metal instead of two as in Fig. 1, there will be less waste of metal 20 stock, and a further saving will be effected due to the fact that the piece from which is formed the U-channel holder for the blade 10 can be made of very thin material as compared with that employed for the handle elements. Also, 25 while three punching and forming dies instead of two will be required, the cost of the extra die will be offset by the reduction in the total cost of die equipment required, because of the simplification and reduction in size of the two dies 30 which replace a single die.

That is, in the embodiment now being described, one sheet metal stamping 28 is employed for providing a U-channel blade holder similar to the holder 14 of Fig. 1, and this from stock of 35 really very thin gauge; and two other stampings of sheet metal, able to be made of somewhat heavier stock than that employed for the pieces 11 and 12 of Fig. 1 without more than negligible addition to the total cost of the tool, are employed 40 for the two handle elements. One of these stampings, corresponding to the portion 13 of the piece 11 of Fig. 1, is marked 29, and the other, corresponding to the piece 12 of Fig. 1, is marked 30.

The two stampings 28 and 29, the former of 45 which is slightly laterally enlarged at the inner end of its U-channel as illustrated in Fig. 5 at 31, are adapted for quick permanent assembly into one rigid structure, merely by inserting the upper end of the stamping 29 into the just-mentioned enlargement of the stamping 28, which enlargement is merely to the extent of the thickness of the stamping 29, and by then applying, in addition to the mounting rivet for the spring 55 23, another rivet 32.

Referring to the stamping 30, this at its upper end is shaped to an arcuate curvature 33 like the corresponding piece 12 of Fig. 1, and this curvature 33 matches and so bears against a similar terminal shaping of the adjacent side wall of the stamping 28; and for symmetry of appearance both the side walls of this stamping 28 are of identical shape at their ends adjacent to the stamping 30.

While I have shown and described what I now consider to be two of the most practical structures according to the invention, it will be understood that various changes and modifications may be resorted to within the scope of the appended 70 claims.

I claim:

1. A hack-saw frame having a plate-like portion at one end extended laterally to form part of the thickness of a handle; an auxiliary plate 75

pivotedly mounted on said portion for increasing the thickness of the handle; and a shear means partially carried by said portion and partially carried by said auxiliary plate and including parts presenting a cutting edge on said portion and a complementary cutting edge on said auxiliary plate.

2. A hack-saw frame having a plate-like portion at one end extended laterally to form part of the thickness of a handle; an auxiliary plate pivotedly mounted on said portion for increasing the thickness of the handle; and a shear means comprising a pair of oppositely facing cutting edges one carried by said portion and the other carried by said plate and relatively moved for cutting action when said portion and said auxiliary plate are relatively rotated about their point of pivotal connection.

the cutting edge on said plate faces the free end of the handle.

8. A hack-saw frame as in claim 5, in which the cutting edge on said plate faces the free end of the handle and has a general line of extension away from near the pivotal connection between said portion and said plate, and in which the other cutting edge also has a general line of extension away from near said pivotal connection, said two lines of extension being so related that when said plate is swung about said pivotal connection to separate said plate and said portion in open-scissor fashion said edges are separated open-scissor fashion and when said plate is swung in the opposite direction to restore it to normal position on said portion said edges are moved toward each other and then one past another to closed-scissor condition.

3. A hack-saw frame having a plate-like portion at one end extended laterally to form part of the thickness of a handle; an auxiliary plate flatwise engaging and pivotedly mounted on said portion for increasing the thickness of the handle; and a shear means comprising a pair of oppositely facing cutter elements one carried by said portion and the other carried by said plate and relatively moved for cutting action when said plate is rotated about its pivotal mounting from a position out of, to a position into, substantial alignment with said portion.

9. A hack-saw frame having a plate-like portion at one end extended laterally to form part of the thickness of a handle; an auxiliary plate pivotedly mounted on said portion for increasing the thickness of the handle, said plate being pivoted to said portion near the end of the handle remote from its free end, and the two handle parts, along a grip length of the handle between the free end thereof and the point of pivoting of the plate thereon, being of substantially the same width and having front and rear edge shapings which substantially match when said plate is in its normal position on said portion; and shear means including a lateral extension on said portion mainly below said point of pivoting and a lateral extension on said plate mainly above said point of pivoting, one of said extensions having an edge constituting one member of a pair of snip elements and the other of said extensions having an edge constituting the other and cooperant member of said pair of snip elements.

4. A hack-saw frame as in claim 2, in which said auxiliary plate is pivoted to said portion at a point near said shear means, and said means is near the end of the handle remote from its free end.

5. A hack-saw frame having a plate-like portion at one end extended laterally to form part of the thickness of a handle; an auxiliary plate pivotedly mounted on said portion for increasing the thickness of the handle, said plate being pivoted to said portion near the end of the handle remote from its free end, and the two handle parts, along a grip length of the handle between the free end thereof and the point of pivoting of the plate thereon, being of substantially the same width and having front and rear edge shapings which substantially match when said plate is in its normal position on said portion; and shear means including a cutting edge on said portion and an oppositely facing coating cutting edge on said plate, each of said edges extended at an angle to the general line of extension of said grip length, whereby said shear means is operable by relative movement between said portion and said plate about the point of pivotal connection therebetween.

10. In a tool for the purpose described, a hack-saw frame including a blade-carrier bent along a longitudinal line of fold to provide a U-channel formed of a single strip of sheet metal, said strip forming part of a single piece of sheet metal the other part of which is extended laterally from said strip and in a plane containing one of the sides of said channel to form a hack-saw handle; means for increasing the thickness of said handle to substantially twice the thickness of said piece of sheet metal comprising an auxiliary plate pivotedly mounted on said handle near the inner end thereof and on the side of the handle offset from which is the other side of said channel; and shear means comprising a pair of oppositely facing snip elements one formed on the handle and the other formed on said auxiliary plate and relatively moved for cutting action when said plate is rotated on the handle about the point of pivotal connection between the handle and plate.

NICHOLAS V. CASSON. 60

- 20 5. A hack-saw frame having a plate-like portion at one end extended laterally to form part of the thickness of a handle; an auxiliary plate flatwise engaging and pivotedly mounted on said portion for increasing the thickness of the handle; and a shear means comprising a pair of oppositely facing cutter elements one carried by said portion and the other carried by said plate and relatively moved for cutting action when said plate is rotated about its pivotal mounting from a position out of, to a position into, substantial alignment with said portion.
- 25 6. A hack-saw frame as in claim 5, in which said auxiliary plate is pivoted to said portion at a point near said shear means, and said means is near the end of the handle remote from its free end.
- 30 7. A hack-saw frame as in claim 5, in which
